UNITED STATES PATENT OFFICE.

WILLIAM LUTHER HUMPHREYS, OF SARASOTA, FLORIDA.

DISPENSING-COUNTER.

1,339,652.

Specification of Letters Patent. Patented May 11, 1920.

Application filed July 11, 1919. Serial No. 310,191.

To all whom it may concern:

Be it known that I, WILLIAM L. HUMPHREYS, a citizen of the United States, residing at Sarasota, in the county of Manatee 5 and State of Florida, have invented certain new and useful Improvements in Dispensing-Counters, of which the following is a specification, reference being had to the accompanying drawings.

10 This invention relates to store furnishings, and particularly to counters.

The general object of my invention is to provide a store counter of ordinary form, but having therein a plurality of rotatably 15 and slidably mounted bins normally entirely housed within the counter, but shiftable to a position where the contents may be removed by the clerk behind the counter, and in this connection to provide a bin so mounted that 20 it will be returned to its original and housed position with the contents fully protected when released by the clerk.

Another object is to provide pedal operated means for shifting the bin to its open or 25 discharge position.

Another object of this invention is to provide a counter of the character before stated with a compartment designed to hold cheese or other like commodity, the bottom of the 30 compartment being provided with a slide upon which the commodity is designed to rest, which slide is actuated by a pedal to withdraw it from the compartment, the compartment being provided with a drawer, 35 opened when it is desired to withdraw the slide, carrying the commodity to a position where the cheese may be cut.

A further object is to provide a construction of this character which is particularly 40 convenient for the display of goods and the dispensing thereof, and to provide a suitable support for paper bags of various characters and sizes in accordance with the commodity being spent and which will form a proper support for rolls of paper, weighing 45 scales, twine receptacles, etc.

Other objects will appear in the course of the following description.

My invention is illustrated in the accompanying drawings, wherein:—

Figure 1 is a front elevation of a counter constructed in accordance with my invention;

Fig. 2 is a rear elevation thereof, partly 55 in section;

Fig. 3 is section on the line 3—3 of Fig. 2;

Fig. 4 is a section on the line 4—4 of Fig. 2;

Fig. 5 is a fragmentary section on the line 5—5 of Fig. 3.

Referring to these drawings, it will be seen that the counter comprises a front wall 10 which may be of one single panel or a plurality of panels, this front wall extending the entire length of the counter and having a top 11. Below the top 11 is a longitudinally extending panel or panels 12 divided to form a plurality of display compartments 13 which are relatively shallow, the front of these compartments being 15 formed by a glass panel 14 whereby the contents of the compartments may be observed. There is one of these compartments for each bin which is disposed beneath the counter, and each compartment is designed to indicate the character of the goods carried within its corresponding bin, the compartments being filled full so that apparently the observer is looking into the bin itself. The top 11 extends nearly the entire length of 20 the counter, but at one end the counter is formed with a cheese compartment 15, the top of which may be formed of glass and the front of which has a glass panel 16. The bottom of this compartment is formed 25 by a slide 17 and the back of the compartment has a hinged door 18 which, when it is open, permits the slide to be pulled out. This slide 17 rests upon a transversely extending board 19 forming the bottom of the 30 cheese compartment 15, this board being slotted and the slide being provided with a downwardly extending arm 20 engaged by a bell-crank lever 21, the extremity of which 35 lever extends out through the back of the counter and is formed to provide a pedal 22. A spring 20' causes the retraction of the slide when the pedal is released. It will be obvious now that by opening the door 18 and depressing the pedal 22, the slide may 40 be shifted outward to carry with it the cheese and the cheese knife or cutter which is usually used in dispensing cheese. Normally, the cheese is entirely protected from the attacks of flies or other insects, being 45 entirely housed within the compartment 15.

At the back of the counter there is a panel 23 with a plurality of openings 24, and vertical and transverse members divide the space between the front and rear walls 110 of the panel in a plurality of compartments. The transverse members above referred to

and designated 25 form supports for the bins. Each bin is approximately rectangular in form and has a bottom and four sides, the front wall 26 being disposed within the 5 aperture 24 of the rear wall of the counter and normally filling this aperture. Each bin is rotatably mounted upon projecting trunnions 27, which rest upon the transverse members 25, and the bin will also slide 10 longitudinally. The upper end of the bin is curved, and this upper end is partly closed by a transverse sheathing 28. A spring 29 is attached to the rear wall of the counter and the bottom of the bin and tends to resist any rotational movement of the bin 15 and return it to its upright position. A pedal 30 is attached to each bin and so disposed that it may be conveniently operated by the clerk. When it is desired to secure 20 access to a bin, the pedal is depressed, thus causing the bin to rotate upon its axis, in an obvious manner, so that the contents of the bin may be readily removed by means of a scoop. Inasmuch as the bins are disposed 25 entirely within the counter and the counter is closed at its sides and ends, it is obvious that the contents of the bin will be protected from dust and dirt.

Preferably, there will be mounted above 30 one or more of the bins a hinged flap 31 which, when the bin is in its normal position, rests over the opening thereof, preventing the entrance of dust, mice or rats, and the lower face of this closure is provided with a spring clip 32 for holding 35 paper bags. An assortment of paper bags may be held in each spring clip, or the paper bags may be distributed in accordance with the manner in which certain commodities are sold. The top of the compartment 40 is provided with a door or doors 33 whereby access may be had to this spring clip. Thus, if these commodities are normally sold in pound lots, paper bags of 45 this size will be used, or for five pound lots, paper bags of this size will be disposed in conjunction with the bin.

The top of the counter constitutes means 50 for supporting paper rolls 34 adjacent each end and a weighing scale 35 at the middle of the counter.

It will be seen that this counter is very simple, and extremely convenient for dispensing articles of the character stated. It may be used for dispensing sugar, salt, 55 coffee, beans, feed, and like commodities, though it is obvious that it is not limited to this use.

While I have illustrated in the drawing only a relatively few bins, it will be obvious 60 that the longer the counter, the greater the number of bins will be mounted therein.

While I have illustrated a form of my invention which I believe to be particularly effective, yet I do not wish to be limited to 65 this, as it is obvious that many changes might be made therein without departing from the spirit of the invention.

I claim:—

1. A counter having therein a compartment 70 with a hinged door in one vertical wall, a slide resting upon the bottom of said compartment and slidably horizontally out through the space normally closed by said door, a pedal mounted in the counter, 75 a rod extending downward from the slide with which the inner end of the pedal is operatively engaged, and a spring normally holding the slide retracted.

2. A counter having therein a compartment 80 with a hinged door, a slide mounted in the compartment and slidably horizontally out through the space normally closed by said door, the bottom of the compartment being formed with a slot extending 85 parallel to the path of movement of the slide, a pedal projecting out from the counter and pivoted in the space inclosed by said counter and having a rearwardly and upwardly projecting portion formed at its 90 extremity with a loop, the slide having a downwardly extending pin passing through said slot in the bottom of the compartment engaged by said loop, and a spring normally holding the slide retracted. 95

In testimony whereof I hereunto affix my signature in the presence of two witnesses.

WILLIAM LUTHER HUMPHREYS.
